WHEEL COVER

Howard M. Jenkins, Jr., Detroit, Mich., assignor
to Van Auken, Inc., Detroit, Mich., a corpora-
tion of Michigan

Application November 21, 1952, Serial No. 22,396

Term of patent 14 years

(CL. D14—30)

To all whom it may concern:

Be it known that I, Howard M. Jenkins, Jr., a citizen of the United States, residing at Detroit, Wayne County, Michigan, have invented a new, original, and ornamental Design for a Wheel Cover, of which the following is a specification, reference being had to the accompanying drawing, forming a part thereof, in which:

Figure 1 is a front elevational view of a wheel cover showing my new design.

Figure 2 is a profile view showing the contour of the cover of Figure 1.

The broken lines shown in Figure 2 are for illustrative purposes only.

I claim:

The ornamental design for a wheel cover as shown and described.

HOWARD M. JENKINS, JR.
